UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

BAG-FASTENER.

1,080,792.

Specification of Letters Patent.

Patented Dec. 9, 1913.

Application filed August 16, 1913. Serial No. 735,982.

To all whom it may concern:

Be it known that I, HUGO TUECKMANTEL, a citizen of the United States, residing at Irvington, in the county of Essex and State of New Jersey, have invented certain new and useful Improvements in Bag-Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in that class of catches adapted for use with port-folios, music-rolls, pocket-books, and the like; and, the invention has for its principal object to provide a simply and effectively operating locking or holding catch of the general character hereinafter more particularly set forth, and for the purposes above stated, the device comprising a chambered shell or casing, provided with a rotatable lock-pin and bar, and means within the shell or casing which holds the pin, at different partial turns, in relatively non-rotatable positions, and at the same time indicating such held positions of the pin by a perceptible snap.

Other objects of this invention not at this time more particularly enumerated will be clearly understood from the following detailed description of the same.

With the various objects of the invention in view, the said invention consists, primarily, in the novel locking or holding catch hereinafter set forth; and, the invention consists, furthermore, in the novel arrangements and combinations of the several parts comprising the catch, all of which will be more fully described in the following specification, and then finally embodied in the clauses of the claim which are appended to and which form an essential part of this specification.

The invention is clearly illustrated in the accompanying drawings, in which:—

Figure 1 is a front view of the locking or holding catch embodying the principles of the present invention, showing the separable members of the catch in their closed relation; and Fig. 2 is a similar view of the same parts represented in said Fig. 1, but showing the members of the catch in their

separated relation. Fig. 3 is a rear view of the two connected members of the catch in their closed relation, said view being made on an enlarged scale; and Fig. 4 is a transverse vertical section of the same, said section being taken on line 4—4 in said Fig. 3. Fig. 5 is a rear view of the lower main member of the catch with the locking bar-carrying post and the retaining disk or plate for retaining the locking bar in its variously rotated positions, omitted from said view; and Fig. 6 is a perspective view of said retaining disk or plate.

Similar characters of reference are employed in the said above described views to indicate corresponding parts.

Referring now to the several figures of the drawings, the reference-character 1 indicates my novel form of holding or locking catch, the same comprising two separable members or elements, one a lower main member which is adapted to be secured to the body of, and the other an upper member which is adapted to be attached to the flap of a port-folio, music roll, or other suitable article of manufacture with which the said holding or locking catch may be employed. The said lower main member which may be of any suitable conformation and is made in the form of a chambered shell or casing comprising a face-plate 2, is surrounded by a downwardly extending wall, as 3, so as to provide a suitable chamber, as 4. Extending in opposite directions from the said shell or casing are suitably formed ears or lugs, 5, provided with suitably disposed holes or perforations 6 for the reception of rivets, or the like, by means of which the shell or casing may be secured in its proper position to the body of the article of manufacture with which the catch is to be used. Extending across the upper part of said shell or casing is a straight wall, as 7, said wall providing a stop to the downward movement of the upper member, to be presently described, when the parts of the catch are brought into their closed relation. Extending in an upward direction from said wall 7 is a plate-like grinding member 8 which is provided with a forwardly projecting stud 9, as shown more particularly in Figs. 4 and 5 of the drawings.

The upper member or element of the holding or locking catch is made in the form of a plate 10 which is provided with suitably

disposed holes or perforations 11 for the reception of rivets, or other fastening means, for attaching the plate to the flap of a portfolio, music roll, or the like. At its lower and straight edge-portion 12, the plate is formed with a rearwardly extending part 13 and an upwardly projecting portion 14, the said plate 10 and said upwardly projecting portion 14 providing two parts 10 which are adapted to embrace the flap of the port-folio, or the like, when the plate 10 is secured in place, as will be clearly evident. The said upwardly projecting portion 14 is provided with a hole or perforation 15 of the proper size into which the previously-mentioned stud 9 of the lower main member is inserted, in the manner indicated in Figs. 3 and 4 of the drawings, when the parts are brought into their closed relation shown in said figures. The said lower main member is provided in its face-plate 2 with an outwardly extending arc-shaped rib or projection, as 16, and concentric with said rib or projection 16, the said 25 plate is also provided with a series of inwardly projecting arc-shaped ribs or projections 17, usually four of such ribs or projections 17 being employed, and such ribs or projections being of such length, so 30 that a depressed part or space 18 will be provided between the ends of the respective adjacent ribs or projections 17, as will be clearly seen from an inspection of Fig. 5 of the drawings. The said face-plate 2 is 35 also provided with a centrally disposed hole or perforation 19 forming a suitable bearing in which is rotatably disposed a pivot-pin 20. Suitably fixed to the outer end-portion of said pin 20, so as to rotate with the 40 same, is a holding or locking bar 21, the said bar being provided at its end-portions with knobs or projections 22, providing suitable fingerpieces for manipulating said bar, and the rear surface of the bar riding 45 upon and bearing in frictional sliding engagement upon the outwardly extending arc-shaped rib or projection 16 of the face-plate 2, as clearly shown in Figs. 1, 2 and 4 of the drawings. Suitably fixed upon the 50 inner end-portion of said pivot-pin 20, which projects into the chamber 4, is a retaining disk or plate, as 23, said disk or plate being preferably made cup-shaped, as indicated in Fig. 6 of the drawings, and 55 having a marginal flange, as 24. Upon oppositely disposed portions, this flange is slotted, as at 25 and 26, so as to provide a pair oppositely projecting and slightly downwardly extending spring-fingers 27 and 28. Upon their free end-portions, these fingers are made with V-shaped, or other suitably shaped, holding or retaining elements or members 29 which are adapted to slide upon said inwardly projecting arc-shaped ribs or projections 17, and are re-

spectively adapted, when the bar 21 and pivot-pin 20 are rotated, to positively snap or spring into removable holding or retaining engagement with the oppositely located depressed parts 18 formed between the ends of the adjacent ribs or projections 17, in the manner clearly represented in Figs. 3 and 4 of the drawings. The assembled arrangement of the parts is such, that a binding frictional relation of the bar 21 and the retaining disk or plate 23 with the opposite sides of the face-plate 2 will be had, but such binding frictional relation of the parts being insufficient to prevent the manipulation and ready rotation of the bar 21 from its locking relation into its unlocked relation, and vice versa.

The manipulation of the catch and its operation will be clearly understood from the foregoing description of the present invention, and from an inspection of the several figures of the drawings, and a further description of the same is therefore deemed unnecessary; and, it will be evident from the foregoing description of the present invention that I have devised a simply constructed and neat catch, the two holding members of which, when the parts are in their locked relation, can not become accidentally unlatched, and the two members being positively retained in their latched relation, until the bar 21 is manipulated by the operator.

I am aware that some changes may be made in the general arrangements and combinations of the various devices and parts, as well as in the details of the construction of the same, without departing from the scope of the present invention as set forth in the foregoing specification and as defined in the clauses of the claims which are appended thereto. Hence, I do not limit my present invention to the exact arrangements and combinations of the said devices and parts as described in the said specification, nor do I confine myself to the exact details of the construction of the said parts as illustrated in the accompanying drawings.

I claim:—

1. A catch for portfolios, and the like, comprising a lower and an upper member, said lower member being made in the form of a chambered shell or casing, a plate-like member extending upwardly from said chambered shell or casing, a retaining means connected with said plate-like member and said upper member for bringing said lower and upper members into locked engagement, a pivot-pin rotatably connected with said chambered shell or casing, a holding bar mounted upon said pin for rotating said pin, and a retaining disk within said chambered shell or casing also mounted upon said pin, and means connected with said disk in slidably retaining engagement with the inner

surface-portions of said shell or casing for retaining said holding bar in its variously rotated positions.

2. A catch for portfolios, and the like, comprising a lower and an upper member, said lower member being made in the form of a chambered shell or casing, a plate-like member extending upwardly from said chambered shell or casing, a retaining means connected with said plate-like member and said upper member for bringing said lower and upper members into locked engagement, a pivot-pin rotatably connected with said chambered shell or casing, a holding bar mounted upon said pin for rotating said pin, and a retaining disk within said chambered shell or casing also mounted upon said pin, and spring-fingers connected with said disk, said fingers being provided at their free ends with retaining elements in slidable engagement with said ribs and adapted to be brought into retaining engagement with said retaining depressions for retaining said holding bar in its variously rotated positions.

3. A catch for portfolios, and the like, comprising a lower and an upper member, said lower member being made in the form of a chambered shell or casing, a plate-like member extending upwardly from said chambered shell or casing, a retaining means connected with said plate-like member and said upper member for hinging said lower and upper member into locked engagement, a pivot-pin rotatably connected with said chambered shell or casing, a holding bar mounted upon said pin for rotating said pin, and a retaining disk within said chambered shell or casing also mounted upon said pin, and said chambered shell or casing being provided with a series of inwardly projecting arc-shaped ribs formed with retaining depressions between said ribs, and means connected with said disk in slidable engagement with said ribs and adapted to be brought into retaining engagement with said retaining depressions for retaining said holding bar in its variously rotated positions.

4. A catch for portfolios, and the like, comprising a lower and an upper member, said lower member being made in the form of a chambered shell or casing, a plate-like member extending upwardly from said chambered shell or casing, a retaining means connected with said plate-like member and said upper member for bringing said lower and upper members into locked engagement, a pivot-pin rotatably connected with said chambered shell or casing, a holding bar mounted upon said pin for rotating said pin, and a retaining disk within said chambered shell or casing also mounted upon said pin, and said chambered shell or casing being provided with a series of inwardly projecting arc-shaped ribs formed with re-

taining depressions between said ribs, and spring-fingers connected with said disk, said fingers being provided at their free ends with retaining elements in slidable engagement with said ribs and adapted to be brought into retaining engagement with said retaining depressions for retaining said holding bar in its variously rotated positions.

5. A catch for portfolios, and the like, comprising a lower and an upper member, said lower member being made in the form of a chambered shell or casing, a plate-like member extending upwardly from said chambered shell or casing, a retaining means connected with said plate-like member and said upper member for bringing said lower and upper members into locked engagement, said shell or casing being provided in its face-plate with an outwardly extending arc-shaped rib, a pivot-pin rotatably connected with said chambered shell or casing, a holding bar mounted upon said pin for rotating said pin, said bar being in slidable frictional engagement with said outwardly extending rib, and a retaining disk within said chambered shell or casing also mounted upon said pin, and means connected with said disk in slidable retaining engagement with the inner surface-portions of said shell or casing for retaining said holding bar in its variously rotated positions.

6. A catch for portfolios, and the like, comprising a lower and an upper member, said lower member being made in the form of a chambered shell or casing, a plate-like member extending upwardly from said chambered shell or casing, a retaining means connected with said plate-like member and said upper member for bringing said lower and upper members into locked engagement, said shell or casing being provided in its face-plate with an outwardly extending arc-shaped rib, a pivot-pin rotatably connected with said chambered shell or casing, a holding bar mounted upon said pin for rotating said pin, said bar being in slidable frictional engagement with said outwardly extending rib, and a retaining disk within said chambered shell or casing also mounted upon said pin, and spring-fingers connected with said disk, said fingers being provided at their free ends with retaining elements in slidable engagement with the inner surface portions of said shell or casing for retaining said holding bar in its variously rotated positions.

7. A catch for portfolios, and the like, comprising a lower and an upper member, said lower member being made in the form of a chambered shell or casing, a plate-like member extending upwardly from said chambered shell or casing, a retaining means connected with said plate-like member and

said upper member for bringing said lower and upper members into locked engagement, said shell or casing being provided in its face-plate with an outwardly extending arc-shaped rib, a pivot-pin rotatably connected with said chambered shell or casing, a hold

5 shaped rib, a pivot-pin rotatably connected with said chambered shell or casing, a holding bar mounted upon said pin for rotating said pin, said bar being in slidable frictional engagement with said outwardly extending rib, and a retaining disk within said chambered shell or casing.

10 rib, and a retaining disk within said chambered shell or casing also mounted upon said pin, said chambered shell or casing being provided with a series of inwardly project-

20 bar in its variously rotated positions.

8. A catch for port-folios, and the like, comprising a lower and an upper member, said lower member being made in the form of a chambered shell or casing, a plate-like member extending

25 of a chambered shell or casing, a plate-like member extending upwardly from said chambered shell or casing, a retaining means connected with said plate-like member and said upper member for bringing said lower and upper members into locked engagement.

upper members into locked engagement, said shell or casing being provided in its face-plate with an outwardly extending arc-shaped rib, a pivot-pin rotatably connected with said chambered shell or casing, whereby

35 with said chambered shell or casing, a holding bar mounted upon said pin for rotating said pin, said bar being in slidably frictional engagement with said outwardly extending rib, and a retaining disk with a rib

40 110, and a retaining disk within said chambered shell or casing also mounted upon said pin, said chambered shell or casing being provided with a series of inwardly projecting arc shaped ribs.

projecting arc-shaped ribs formed with retaining depressions between said ribs, and spring-fingers connected with said disk, said fingers being provided at their free ends with retaining elements.

45 with retaining elements in slideable engagement with said ribs and adapted to be brought into retaining engagement with said retaining depressions for retaining said holding bar in its variously rotated positions.

9. A catch for portfolios, and the like, comprising a lower and an upper member, said lower member being made in the form of a chambered shell or casing, a plate-like

55 a chambered shell or casing, a plate-like member extending upwardly from said chambered shell or casing, a retaining stud projecting forwardly from said plate-like member, said stud being adapted to

member, said stud being adapted to be brought into holding engagement with a 60 perforation with which said upper member is provided, said shell or casing being provided in its face-plate with an outwardly extending arc-shaped rib.

extending arc-shaped rib, a pivot-pin rotatably connected with said chambered shell or casing, a holding bar mounted upon said

pin for rotating said pin, said bar being in
slidable frictional engagement with said
outwardly extending rib, and a retaining
disk within said chambered shell or casing
also mounted upon said pin, and means con-
nected with said disk in slidably retaining
engagement with the inner surface-portions
of said shell or casing for retaining said
holding bar in its variously rotated pos-
itions.

10. A catch for portfolios, and the like, comprising a lower and an upper member, said lower member being made in the form of a chambered shell or casing, a plate-like member extending upwardly from said chambered shell or casing, a retaining stud projecting forwardly from said plate-like member, said stud being adapted to be brought into holding engagement with a perforation with which said upper member is provided, said shell or casing being provided in its face-plate with an outwardly extending arc-shaped rib, a pivot-pin rotatably connected with said chambered shell or casing, a holding bar mounted upon said pin for rotating said pin, said bar being in slidable frictional engagement with said outwardly extending rib, and a retaining disk within said chambered shell or casing also mounted upon said pin, and spring-fingers connected with said disk, said fingers being provided at their free ends with retaining elements in slidable engagement with the inner surface portions of said shell or casing for retaining said holding bar in its variously rotated positions.

11. A catch for portfolios, and the like, comprising a lower and an upper member, said lower member being made in the form of a chambered shell or casing, a plate-like member extending upwardly from said chambered shell or casing, a retaining stud projecting forwardly from said plate-like member, said stud being adapted to be brought into holding engagement with a perforation with which said upper member is provided, said shell or casing being provided in its face-plate with an outwardly extending arc-shaped rib, a pivot-pin rotatably connected with said chambered shell or casing, a holding bar mounted upon said pin for rotating said pin, said bar being in slideable frictional engagement with said outwardly extending rib, and a retaining disk within said chambered shell or casing also mounted upon said pin, said chambered shell or casing being provided with a series of inwardly projecting arc-shaped ribs formed with retaining depressions between said ribs, and means connected with said disk in slideable engagement with said ribs and adapted to be brought into retaining engagement with said retaining depressions for retaining said holding bar in its variously rotated positions. 105 110 115 120 125

12. A catch for portfolios, and the like, comprising a lower and an upper member, said lower member being made in the form of a chambered shell or casing, a plate-like member extending upwardly from said chambered shell or casing, a retaining stud projecting forwardly from said plate-like member, said stud being adapted to be brought into holding engagement with a perforation with which said upper member is provided, said shell or casing being provided in its face-plate with an outwardly extending arc-shaped rib, a pivot-pin rotatably connected with said chambered shell or casing, a holding bar mounted upon said pin for rotating said pin, said bar being in slideable frictional engagement with said outwardly extending rib, and a retaining disk within said chambered shell or casing also mounted upon said pin, said chambered shell or casing being provided with a series of inwardly projecting arc-shaped ribs formed with retaining depressions between said ribs, and spring-fingers connected with said disk, said fingers being provided at their free ends with retaining elements in slidable engagement with said ribs and adapted to be brought into retaining engagement with said retaining depressions for retaining said holding bar in its variously rotated positions.

In testimony, that I claim the invention set forth above I have hereunto set my hand this 13th day of August, 1913.

HUGO TUECKMANTEL.
